ESCAPEMENT DEVICE

Thomas L. D. Lynxwiler, Ingleside, Ill., assignor
to Mills Industries, Incorporated, Chicago, Ill.,
a corporation of Illinois

Application September 9, 1948, Serial No. 48,471

4 Claims. (Cl. 74—112)

1

This invention relates to escapement mechanisms and has as an important object the provision of an escapement device which will prevent both clockwise and counter-clockwise rotation of a shaft, and which, upon operation of the device, will allow the shaft to be rotatably advanced a predetermined number of degrees in one direction.

Another object of the invention is to provide an escapement device of the above character which will prevent counter-rotation of said shaft during the operation of the device.

Still another object of the invention is to provide, in an escapement device having the aforesaid characteristics, parts alternately engageable with an escapement wheel to allow rotative advancement of the latter and at the same time to prevent an uncontrolled rotation of said wheel.

Other objects and advantages, such as the simplicity of the parts, will be apparent from the following description of a preferred embodiment thereof, taken in connection with the accompanying drawing, in which:

Fig. 1 is a cross-sectional view of an escapement device of my invention showing the parts thereof in their normal positions in which the rotation of an escapement wheel is prevented;

Fig. 2 is a similar view of the device showing the position of the parts therein when said parts are moved to free said wheel for rotation; and

Fig. 3 is a like view showing the parts being returned to their normal positions by the rotation of said wheel.

In the drawing the numeral 10 indicates generally a block of metal or the like within which is provided a race 11 having opposing parallel surfaces 12 and 13 adapted to receive opposite sides 14 and 15 (Fig. 2) of a reciprocatable pallet shown generally at 16. A shaft 17 extends through the block 10 at right angles to the race 11 and has fixed thereon, in any suitable manner, an escapement wheel 18 disposed in a plane with the pallet. Said wheel has thereon a plurality of teeth 19, each of said teeth being formed by a chordal surface 20 and a radial surface 21 on the wheel 18.

The pallet 16 has an inner vertical surface 22 extending upwardly from its lower side 14 to form a heel 23, and from the inner side of the pallet a finger 24 extends above the escapement wheel 18. On the extremity of the finger is formed a depending hook member 25 having thereon a substantially vertical surface 26.

Although it will be understood that the pallet 16 may be reciprocated manually or otherwise, I

have shown, for purposes of illustration, a solenoid 27 suitable for operating said pallet. Said solenoid may be provided with a retractable armature 28 which may be fastened to the pallet as by a bolt 29 passed through the end of the armature and through the outer end of said pallet.

The form of the invention illustrated in the drawing and described above is adapted to allow rotatable advancement of the shaft 17 in a clockwise direction, as viewed in the drawing, torque from an outside source (not shown) being applied to the shaft to rotate the same in said clockwise direction. Said device is readily adaptable, for example, for use in dispensing machines and the like, such as the dispensing machine which I have described in my copending application, Serial No. 54,939, filed concurrently herewith, wherein it is necessary that a dispensing element be allowed to rotate a predetermined number of degrees each time a dispensing operation takes place.

In its normal condition the pallet 16 is disposed in the position shown in Fig. 1, the heels 23 being in engagement with one of the teeth 19 on the wheel 18. In this position it will be seen that the surface 14 of the pallet lays flat against one of the radial surfaces 21 of the wheel and the vertical surface 22 of the pallet lays flat against one of the chordal surfaces 20 of said wheel, thus preventing rotation of the wheel 18 and shaft 17 in either direction.

Upon energization of the solenoid 27 the armature 28 is moved to the left, as seen in the drawing, and the pallet 16 is moved to the position shown in Fig. 2, the heel 23 being disengaged from the wheel and the hook member 25 being simultaneously brought into the path of the teeth 19 on said wheel with the surface 26 on the hook engaging one of the radial surfaces 21 on the wheel and the bottom surface of the hook laying flat along an adjacent chordal surface 20. In this position it will be understood that hook member 25 prevents counterclockwise rotation of the wheel 18 and, for so long as the solenoid is energized, prevents clockwise rotation of said wheel. When the solenoid 27 is de-energized, however, clockwise torque applied to the shaft 17 will rotate the wheel in a clockwise direction, the uppermost tooth 19 of the wheel carrying the hook member 25, and thus the pallet 16, to the right and toward its normal position. As the latter tooth moves the hook member 25 out of the path of the teeth, the heel 23 of the pallet is moved into said path to engage the next tooth (indicated by 55 19a). Engagement of the tooth 19a with the

heel 23 stops the rotation of the wheel 18 and the shaft 17, and with said engagement all of the parts will have been returned to the normal positions thereof as illustrated in Fig. 1, the heel 23 re'aining the wheel in its newly rotated position.

It will be seen that, in the manner above described, the wheel 18 may be rotatably advanced a predetermined number of degrees each time the pallet is moved to the left as seen in the drawing. It will further be evident, however, that regardless of the position of the pallet 16, counter-rotation of the shaft 17 and the wheel 18 will be impossible and uncontrolled rotation of the wheel and shaft will at all times be prevented.

The foregoing detailed description has been given for clearance of understanding only, and no unnecessary limitations should be understood therefrom, for it will be apparent that various changes may be made in the form and construction of the device of my invention without departing from the spirit and scope of the invention.

I claim:

1. An escapement device comprising, a rotatable wheel, a plurality of evenly spaced teeth on the circumference of said wheel, each of said teeth having a radial surface and a chordal surface thereon, a heel simultaneously engageable with a radial surface of one of said teeth and a chordal surface of an adjacent tooth thereby preventing rotation of said wheel in any direction while said heel is in engagement with said surfaces, and a member engageable with said wheel and with the chordal surface of a third tooth on said wheel in the disengagement of said heel from the surfaces of said first teeth, said member preventing rotation of said wheel in one direction and being movable to disengaging position by rotation of said wheel in another direction, said heel being moved into engaging position in the disengagement of said member from said wheel.

2. An escapement device comprising, a rotatable wheel, a plurality of evenly spaced teeth on the circumference of said wheel, each of said teeth having a radial surface and a chordal surface thereon, a reciprocable pallet, a heel on said pallet simultaneously engageable with a radial surface of one of said teeth and a chordal surface of an adjacent tooth thereby preventing rotation of said wheel in any direction while said heel is in engagement with said surfaces, and a member on said pallet engageable with said wheel and with the chordal surface of a third tooth on said wheel in the disengagement of said heel from the surfaces of said first teeth, said member preventing rotation of said wheel in one direction and being movable to disengaging position by rotation of said wheel in another direction, said

5 heel being moved into engaging position in the disengagement of said member from said wheel.

3. An escapement device comprising, a rotatable wheel, a reciprocable pallet having a heel engageable with said wheel, said heel having angularly-disposed wheel-engaging surfaces and the wheel having corresponding surfaces arranged to be engaged by said heel at each position of rest of the wheel, thus preventing rotation of said wheel in any direction while said heel is in engagement therewith, means for reciprocating the pallet to disengage said heel from the wheel, and a hook member on said pallet engageable with said wheel upon disengagement of said heel therefrom, said member preventing rotation of said wheel in one direction while in engagement therewith and being movable to disengaging position by rotation of said wheel in another direction, the action of said wheel on said member moving said heel into its initial position in engagement with the wheel and disengaging said member from the wheel.

4. An escapement device comprising a rotatable wheel having a plurality of evenly spaced teeth on the circumference thereof, a reciprocable pallet having a heel provided with angularly-disposed wheel-engaging surfaces simultaneously engageable with correspondingly angularly-disposed surfaces of two adjacent teeth on said wheel, thereby preventing rotation of the latter in any direction while said heel is in engagement with said surfaces, means for reciprocating the pallet to disengage the heel from the wheel, and a hook member on said pallet engageable with a third tooth on said wheel upon disengagement of said heel from said surfaces, said member preventing rotation of said wheel in one direction while in engagement with said third tooth and being movable to disengaging position by rotation of said wheel in another direction, such action of said wheel upon said member moving said heel into its initial position in engagement with the succeeding teeth of the wheel upon disengagement of said member from said third tooth.
